UNITED STATES PATENT OFFICE.

HENRY H. CUTLER, OF MILWAUKEE, WISCONSIN.

PHASE-SPLITTER.

No. 821,023.

Specification of Letters Patent.

Patented May 22, 1906.

Application filed January 7, 1905. Serial No. 240,127.

To all whom it may concern:

Be it known that I, HENRY H. CUTLER, a citizen of the United States, residing at Milwaukee, in the county of Milwaukee and State of Wisconsin, have invented, new and useful Improvements in Phase-Splitters, of which the following is a full, clear, concise, and exact description, reference being had to the accompanying drawings, forming a part 10 of this specification.

My invention relates to phase-splitters, more particularly designed for starting single-phase motors under no load, my object being to provide a simple and efficient device 15 whereby the motor may be readily started.

My invention also contemplates the provision of a phase-splitter in which a plurality of switches are provided for cutting out the resistance of the phase-splitter, which are arranged to be closed one at a time in a definite order and which may be automatically opened.

I have illustrated my invention in the accompanying drawings, in which—

Figure 1 is a view of the switch of my invention. Fig. 2 is a side view thereof, all the arms being removed except the first one. Fig. 3 is a detail view of the retaining-magnet. Fig. 4 is a detail view of the mechanism for holding the levers in the closed position. Fig. 5 is a diagrammatic view of the circuit arrangement of my invention. Fig. 6 is a sectional view of one of the switch-arms, taken on the line 6-6 of Fig. 4; and Fig. 7 is a detail view of one of the locking-dogs.

In constructing my invention switch-levers 1, 2, and 3 are suitably pivoted or journaled to one end and are provided at their opposite ends with handles. I have shown 40 the several switch-levers as journaled upon a shaft or rod 4, mounted in arms upon brackets 6. The brackets 6 also support a rod 7, which is threaded through a rubber tube 8, which serves as a cushion or buffer against 45 which the extended ends of the arms or levers are adapted to impinge when thrown open. The first lever 1 forms a single-pole switch and carries a contact device 9, made in the usual form from a number of strips of 50 copper laid face to face, the free ends being adapted to engage the contact-surfaces to complete the circuit therethrough. The levers 2 and 3 are provided with two arms 10 55 and 12 13, respectively, and thereby form two double-pole switches. Each arm of the

two levers carries a contact device of the same construction as the contact-bar 9. Upon the base-board 14 is mounted a contact-bar 15, with which one end of the contact device 9 of each lever is adapted to engage, the other end of said device being adapted to engage one of the contact-terminals 16, 17, 18, 19, and 20. Upon the terminal 16 is provided a binding-post 21, by which the same may be connected with one side of the supply-circuit. Upon the terminal 20 is provided, a binding-post 22, whereby the same may be connected with one side of the field-coils, and a second binding-post 23 is provided, which is adapted to be connected with the other side of the field-coils. Upon the terminal 16 is mounted a carbon block 24, and a similar carbon block 25 is mounted upon the end of the contact-bar 15. The first switch-arm 1 carries laterally-extending 75 arms 26 and 27, supporting upon the ends the carbon blocks 28 and 29, respectively. When the switch-arm 1 is moved to close the circuit, the block 29 engages block 25 and block 28 engages block 24, thereby closing the circuit from the terminal 16 to terminal 15. The further movement of the switch-arm causes the contact device 9 to directly close together terminals 15 and 16. Likewise when the switch-arm 1 is moved outward 85 the contact device 9 leaves terminals 15 and 16 before the carbon blocks separate, so that any arc which may be formed by the opening of the circuit will take place between the carbon blocks instead of the metallic surfaces. 90 Near the upper end of the switch-arm a lug 30 is provided which carries a laterally-extending rod 31, which may take the form of a screw.

Mounted upon the base-board 14 above the arm 1 is a retaining-magnet 32, having an armature 33, pivoted at 34. The armature 33 carries a laterally and upwardly extending lug 35, and when the arm 1 is moved to close the circuit the rod 31 engages the side of the armature to move the same against the magnet-pole and the magnetism of the magnet 32 retains the armature in this position. The swinging end of the armature carries the lug 35 upon the exterior of the rod 31, so that said rod will rest in the slot formed between the lug 35 and the face of the armature. So long as the magnet 32 remains energized the arm 1 will thus be held in a closed position. When, however, the magnet is deenergized, the 110

weight of the arm will carry the same to the position shown in Fig. 2, thereby rocking the armature upon its pivot, as shown.

Mounted upon a rod or shaft 37, supported 5 in suitable bearings upon the base-plate 14, are locking-dogs 38 and 39. Each dog has a rear end so shaped as to engage the base-plate 14 and limit the downward movement of the dog when free. Upon the end of the dog to 10 the right an upwardly-extending lip 40 is provided, which has its front edge curved and its rear edge perpendicular to the upper surface of the dog. The under side of the dog has a lip 41, extending throughout its entire 15 length, which lip is rounded off at its left-hand edge. The levers 2 and 3 are each provided with a latch 42, pivoted to the arm at 43 and set in a slot 44. The wall of the slot limits the vertical movement of the latch 20 relatively to the arm. Below the latch and formed integrally with the arm is a lug 45, projecting toward the base-plate, and consists of two parts 46 and 47, the part 46 being square in section and flat upon the end, and 25 when the lever is in a position to close the circuit presents a vertical surface. The upper part of the part 47 is inclined or chamfered at an acute angle.

In Fig. 5 I have shown a diagrammatic 30 view of the circuit arrangement of my device, and it will be noted that one side 48 of the supply-main branches so as to include two sets of coils in parallel. I have shown four field-coils 49, 50, 51, and 52; but it will be 35 understood that I have only selected this number for the purpose of illustration. One side 48 of the supply-main is connected through the coils 49 and 50 and by conductor 53 with binding-post 22 on the contact 20. The contact 20 is connected with one end of 40 the non-inductive resistance 54, the opposite end thereof being connected by conductor 61 with the contact 15. At an intermediate point the non-inductive resistance is connected by conductor 56 with the contact 18. A branch 57 of the main 48 is connected 45 through the field-coils 51 and 52 by conductor 58 with binding-post 23. The binding-post 23 is connected by conductor 59 with contact 19, said contact being also connected with one end of the inductive resistance 60. The opposite end of the resistance 60 is connected by conductor 61 with contact 15 and at an intermediate point is connected by conductor 62 with the contact 17. The contact 21 is connected by wire 63 with the opposite side 63 of the supply-main. The retaining-magnet 32 is supplied with a direct current from any suitable source, and in the present 55 instance is illustrated as receiving a direct current from the alternating-current mains 48 and 63 through the interposition of a rectifier 64. This rectifier may be of any desirable construction and is illustrated as a rectifier of the aluminium-iron type, in which

the longer transverse lines 65 represent, say, iron, while the shorter lines 66 represent, say, aluminium. The current from the alternating-current circuit will pass between these metals in one direction only. Accordingly 70 with the cells disposed as illustrated a rectified current will be delivered to the retaining-magnet.

In operation, assuming that it be desired to start the motor, the main switch having 75 been closed, the switch-arm 1 is closed to first close the circuit between the carbon blocks and finally close together the terminals 15 and 16 directly through the contact device 9. The armature 33 is engaged and 80 moved against the pole of the retaining-magnet 32, and the retaining-magnet thus serves to maintain the switch-arm 1 in a closed position. Current may now be traced from supply-main 63, contact 16, across the switch-arm 1, contact 15 to conductor 61, where it will divide, part thereof passing through the non-inductive resistance 54 to contact 20, by conductor 53, through the field-coils 50 49, and thence to the opposite main 48, the other 85 part of the current passing through the inductive resistance 60 to the binding-post 23, by conductor 58, through the field-coils 52 51, and thence by conductor 57 to the opposite main 48. A direct current will at the same 90 time pass through the retaining-magnet 32, energizing the same. The second switch-arm 2 is now closed, and as the dog 38 is in its raised position the latch 42 of the arm will ride over the lip 40 of the dog 38 and will 95 engage the vertical wall thereof, and the switch-arm will thus be held in the closed position. With this arm closed circuit may be traced from the conductor 63, contact 16, across switch-arm 1, by pole 11, conductor 100 105 56, through one-half of the resistance 54 to contact 20, thence by conductor 53, through the field-coils 50 and 49 back to the opposite side 48 of the main. A branch circuit may also be traced from contact 15, through pole 110 10, conductor 62, through one-half of the resistance 60 to binding-post 23, and thence by conductor 58 through field-coils 52 and 51 and branch 57 back to the opposite side 48 of the main. In this manner a portion of the resistances 54 and 60 is cut out. The wall 47 of the arm 2 will engage and lift the second 115 rocking dog 39, so that when arm 3 is closed the latch 42 thereof will be engaged and held by the lip 40 of the dog 39. When the arm 3 is closed, the circuit may be traced from conductor 120 15 through the pole 13 of the switch-arm 3 to the contact 20, and thence by conductor 53 through the field-coils 50 and 49 to the opposite side 48 of the main line, and a 125 branch circuit may be traced through the pole 12 of the switch-arm 3 to binding-post 23, and thence by conductor 58 through field-coils 52 and 51 and branch 57 to the opposite side 48 of the main line, in this manner con- 130

necting the primary windings of the motor directly across the line and removing all resistance therefrom.

If it is desired to cut in resistance and open circuit through the motor, retaining-magnet 32 may be deenergized in any suitable manner, and the arm 1 will be released and fly outward to the position shown in Fig. 2. In moving outward the first rocking dog 38 is permitted to fall and the latch of the second switch-arm 2 is thus released and said switch-arm likewise flies out. The switch-arm 2 permits the second rocking dog to fall, thereby releasing the switch-arm 3, whereby all the switch-arms are released and the circuit to the motor is opened.

Having described my invention, what I claim as new, and desire to secure by Letters Patent, is—

1. In a phase-splitter, in combination, a plurality of resistances of different character, and a plurality of independently-actuated switches for controlling said resistances, each of said switches being adapted to control all of said resistances.

2. In a phase-splitter, in combination, a plurality of resistances of different character, a plurality of independently-actuated switches controlling said resistances, and means for preventing the closure of said switches except in a definite order.

3. In a phase-splitter, in combination, a plurality of resistances of different character, a plurality of independently-actuated switches for controlling said resistances, and a retaining-magnet for holding said switches in a closed position.

4. In a phase-splitter, in combination, a plurality of resistances of different character, a plurality of independently-actuated switches for controlling the said resistances, and an electromagnetic retaining mechanism for holding said switches in a closed position.

5. In a phase-splitter, in combination, a plurality of resistances of different character, and a plurality of independently-actuated switches for controlling said resistances, an electromagnetic retaining mechanism for holding said switches in a closed position, and means for supplying the same with a direct current.

6. In a phase-splitter, in combination, a plurality of resistances of different character, a plurality of independently-actuated switches for controlling the same, means for preventing the closure of said switches except in a definite order, and a retaining mechanism for holding said switches in a closed position.

6. 7. In a phase-splitter, in combination, a plurality of resistances of different character, a plurality of independently-actuated switches arranged in series for controlling said resistances, an interlocking mechanism, whereby each switch controls the next suc-

ceeding switch, and retaining means for the first switch of the series.

8. In a phase-splitter, in combination, a plurality of resistances of different character arranged in parallel paths, and a plurality of independently-actuated switches for controlling said resistances, each switch being adapted to control all of said resistances.

9. In a phase-splitter, in combination, a plurality of resistances of different character arranged in parallel paths, a plurality of independently-actuated switches for controlling said resistances, and means for preventing the closure of said switches, except in a definite order.

10. In a phase-splitter, the combination with, a plurality of resistances, of different character, arranged in parallel paths, a plurality of independently-actuated switches for controlling said resistances, a retaining mechanism for holding said switches in a closed position, and means for automatically actuating said mechanism to release said switches.

11. In a phase-splitter, in combination, a plurality of resistances of different character arranged in parallel paths, a plurality of independently-actuated switches for controlling said resistances, means for preventing the closure of said switches except in a definite order, and a retaining mechanism for holding said switches in a closed position.

12. In a phase-splitter, in combination, a non-inductive and an inductive resistance arranged in parallel paths, and a plurality of independently-actuated switches for controlling said resistances, each switch being adapted to control both of said resistances.

13. In a phase-splitter, in combination, a non-inductive and an inductive resistance arranged in parallel paths, a plurality of independently-actuated switches for controlling said resistances, and means for preventing the closure of said switches except in a definite order.

14. In a phase-splitter, in combination, a non-inductive and an inductive resistance arranged in parallel paths, a plurality of independently-actuated switches for controlling said resistances, means for preventing the closure of said switches except in a definite order, and a retaining mechanism for holding said switches in a closed position.

15. In a phase-splitter, in combination, a plurality of resistances of different character, and a plurality of independently-actuated switches for simultaneously controlling said resistances, each switch adapted to control both of said resistances.

16. In a phase-splitter, in combination, a plurality of resistances of different character, a plurality of independently-actuated switches for simultaneously controlling said resistances, and means for preventing the closure of said switches except in a definite order.

17. In a phase-splitter, in combination, a plurality of resistances of different character, a plurality of independently - actuated switches for simultaneously controlling said resistances, means for preventing the closure of said switches except in a definite order, and a retaining mechanism for holding said switches in a closed position.

In witness whereof I have hereunto subscribed my name in the presence of two witnesses.

HENRY H. CUTLER.
